(No Model.)

A. VOGT.

FRUIT JAR.

No. 473,100.

Patented Apr. 19, 1892.

UNITED STATES PATENT OFFICE.

AUGUST VOGT, OF WILLOW POINT, TEXAS.

FRUIT-JAR.

SPECIFICATION forming part of Letters Patent No. 473,100, dated April 19, 1892.

Application filed December 23, 1891. Serial No. 415,992. (No model.)

To all whom it may concern:

Be it known that I, AUGUST VOGT, of Willow Point, in the county of Wise and State of Texas, have invented certain new and useful 5 Improvements in Fruit-Jars; and I do hereby declare the following to be a full, clear, and exact description of the invention, such as will enable others skilled in the art to which it pertains to make and use it, reference being 10 had to the accompanying drawings, which form part of this specification.

My invention relates to an improvement in fruit-jars; and it consists in the novel features of construction which will be fully described hereinafter, and more particularly referred to in the claim.

Referring to the accompanying drawings, Figure 1 is a vertical sectional view of my improved fruit-jar. Fig. 2 is a sectional view 20 on the line xx of Fig. 1. Fig. 3 is a detached view of the removable plate. Fig. 4 is a plan view slightly reduced in size.

A represents the body of the jar, B the curved portion forming its upper end, and C 25 the flat square portion made integral with the upper end of the jar and which form a base or foot for the same when inverted for filling or emptying.

Formed around the periphery of the jar at 30 its lower end are the screw-threads D, and immediately above the screw-threads is formed the slight projection E, made flat on its under side, as shown.

G represents the detachable bottom of the 35 jar, formed, preferably, of glass, which is constructed with a vertical wall H, extending entirely around its top surface. The inner side of this wall H is made screw-threaded, so as to engage the threads on the lower end of the 40 jar proper. Placed around the jar immediately beneath the projection E is a rubber ring F, which rests on a shoulder I in the vertical wall H, so that when the bottom G is in position the space between the shoulder I and 45 flange E is filled and sealed by the band F.

J represents a circular groove in the top of the detachable portion G, and placed within this groove is a rubber ring K, as shown, against which bears the lower end of the jar, 50 which assists greatly in preventing any leakage therefrom.

The wall H is extended slightly upward above the screw-threads, as shown, so as to encircle the shoulder portion E, and thus form around the jar a circular trough or cavity for 55 the reception of wax or other sealing material. The walls of this cavity are roughened, as shown, so that the wax may effect a more secure hold thereon. Sealing in this manner, together with the rubber rings above described, effectually prevents any leakage from 60 the jar.

In the upper end of the jar at the point where the contracted or curved portion B begins is formed a series of inwardly-extending 65 projections, and adapted to rest thereon is the removable plate M, having openings or perforations in its body portion and a series of inwardly-cut notches M' on its periphery. These notches register with the projections L 70 and admit of the passage of the said plate above the said projections, and the plate being thus extended is slightly turned, allowing the wider portions of the periphery to rest on the projections, thus supporting the plate in 75 the desired adjustment. The curved wall B acts as a stop and prevents the plate from having any further upward movement.

When the jar is to be filled with fruit, it is placed in an inverted position with the plate 80 M in place. The desired quantity of fruit is then placed in the jar and the remaining space filled with the preserving-liquid or with the fruit sirup. The bottom is then screwed on and the position of the jar reversed. Wax 85 or other sealing substance is then placed around the projection E, filling the space between the jar and the upper portion of the wall H, thus completing an air-tight joint.

The fruit is prevented from rising to the 90 top of the jar by the plate M; but the space above this plate is filled with the liquid, and by this means the entire contents is kept submerged. The preservation of the fruit is thus assured.

The angular plate C rests in a corresponding recess in the table or other support when the jar is being filled, so that when the cover G is applied thereto the jar is held from turning, thus enabling the operator to employ 95 both hands in tightening the portion G in place.

Having thus described my invention, I claim—

In a fruit-jar, the combination, with a jar having an inwardly-curved upper end and a removable bottom portion, of a series of projections at the base of the said curved portion, and a perforated plate having notches formed in its periphery which register with the said

projections and which when turned rest thereon, substantially as shown and described.

In testimony whereof I affix my signature in presence of two witnesses.

AUGUST VOGT.

Witnesses:

J. V. BOGG,
Z. T. FENIMON.
